METHOD AND APPARATUS FOR DISPERSING MATERIALS

Alexander Gordon Galloway, Washington, D. C.;
dedicated to the free use of the People of the
United States of America

Application December 21, 1937, Serial No. 180,996

21 Claims. (Cl. 43—124)

(Granted under the act of March 3, 1883, as
amended April 30, 1928; 370 O. G. 757)

This application is made under the act of March 3, 1883, as amended by the act of April 30, 1928, and the invention herein described and claimed, if patented, may be manufactured and used by or for the Government of the United States for governmental purposes without the payment to me of any royalty thereon.

I hereby dedicate the invention herein described to the free use of the People of the United States of America to take effect on the granting of a patent to me.

This invention relates to a method for dispersing parasitical materials such as insecticides, fungicides, nemacides, germicides, and other materials in dust form, and an apparatus for accomplishing this dispersion.

The main object of this invention is to provide a method for more effectively dispersing such dust materials over surfaces of foliage, battle fields, soil, or on any other surface.

Another object of this invention is to provide a method of dispersing and applying said materials which insures a positive and permanent adherence to the surface applied.

Still another object of this invention is to provide a method of dispersing and applying said dust materials, which method embraces the separate but simultaneous release of said dust material with an adhesive and insures definite relative proportions of the adhesive with the dust material.

A further object of this invention is to provide an apparatus for accomplishing the above-mentioned objects by means of a simple mechanism adapted to vehicles, such as airplanes, autogyros, dirigibles, automobiles, boats or other types of air, land, or water vehicles, either stationary or while in motion.

A still further object of this invention is to provide an apparatus adapted for use on such vehicles which is synchronized to effect a uniform control of dispersion in relation to the velocity of the vehicle and the coverage desired.

A still further object of this invention is to provide an apparatus of the type mentioned which will effect a union of particles of dust and of adhesive so that positive adherence of the dust will occur when it contacts any surface or object. This invention is particularly useful for rapidly spreading dust insecticides with adhesives over large areas.

Heretofore, in the application of insecticides with stickers it has been found necessary to mix the ingredients before dispersion. The object to this practice is the difficulty of maintaining uni-

form dispersion of material from any apparatus without clogging its parts resulting in an inevitable mitigation of efficiency. Another objection is that at present there are no known adhesives which can be added to insecticides, fungicides, nemacides, and germicides in dust form prior to dispersion, which will insure complete and satisfactory adherence of the material. These objections are obviated in the present invention by mixing the ingredients exteriorly to the apparatus and also in such a manner that a high numerical percentage of the particles of adhesive unite with the particles of dust released.

The following description, considered together with the accompanying drawing, will more fully disclose this invention and further objects and advantages thereof will be apparent.

In the drawing:

Figure 1 is an elevational view of this invention in one of its forms for use on air vehicles.

Figure 2 is a cross-sectional view of Figure 1 along the line 2—2, showing adaption to the frame members of an autogyro fuselage.

Figure 3 is a fragmentary cross-sectional view of Figure 1 along the line 3—3 in Figure 2.

Figure 4 is a plan view of the dispersing tube.

Figure 5 is a phantom side view of a portion of the dispersing tube showing a modification of the delivery terminal of the tube hereinafter designated by the numeral 38.

Referring with more particularity to the drawing in which like numerals designate like parts, the numeral 5 designates a hopper of any desired shape for installation in a vehicle. In the drawing the vehicle shown is an autogyro and the hopper is shown within and attached to frame members of its fuselage 6, 6. At the bottom of said hopper, a delivery throat 7 is secured to the feed unit 8. A continuous flight conveyor screw 9 is horizontally mounted in bearings 10 and 11 in the throat of the hopper. Directly beneath said conveyor screw, a second conveyor screw 12, of substantially the same size and design, is mounted in bearings 13 and 14. The flight of each of said conveyor screws is in the same direction. The shafts 15 and 16 upon which the flights of the conveyor screws are mounted extend exteriorly to receive gears 17 and 18 maintained in constant mesh. The shaft 16 is further extended to receive a grooved pulley 19. The said conveyor screws are mounted in tubular troughs 20 and 21 secured together along the line 22. These troughs are made communicable through openings 23 and 24. The trough 20 has its top portion partially open at 25 to permit

entrance of dust material from the hopper, and the trough 21 has an opening 26 to provide means for discharging the dust material out of the said device onto a slide valve 27, substantially as shown.

5 A dispersing tube 28 is secured to the bottom housing of said slide valve 27 by any suitable means so that material passing through said valve falls inside the said tube 28. Hollow air 10 scoops 29, 29 intersect the tube 28 but do not extend into said tube. Said scoops are attached at such an angle that air flowing through them passes into the tube 28 at a tangent to the interior walls. The purpose of the angular attachment of the air scoops 29, 29 is for imparting a 15 rotary and progressive motion to the air introduced by them into the dispersing tube 28. This motion of the air within said tube is desirable for the purpose of thoroughly and uniformly entraining the dust in its rearward travel through the dispersing tube 28. A hollow tube 30 extends axially through the tube 28 and is rotatably mounted in bearings 31 and 32, but any other suitable number of bearings may be used. Bearings 25 such as the bearing 32 are supported by spiders such as 32a. At the terminal of said tube 30 inside the dispersing tube 28, a truncated cone 33 is secured at its smaller end. A disc 34, being somewhat smaller in circumference than the larger base of the truncated cone 33, is 30 coaxially mounted on said cone by means of adjustable studs and nuts 35, 35. The tube 28 carries a bell flange 36, the length of which is such that it terminates slightly forward of the disc 34. 35 The forward end of said tube 30 has keyed to it a grooved pulley 37.

A stationary tube 38 is longitudinally disposed within the spinner tube 30 and extends a short distance within the cone 33. This extension may 40 terminate in a plurality of openings, such as the nipple 50 in Figure 5. This tube 38 may be appreciably smaller in diameter than the inside diameter of the tube 30, since no seal is necessary between these two elements. Bearings 39, 39, 39 are utilized to minimize friction between 45 tubes 30 and 38. The stationary tube 38 is connected to the delivery side of feed pump 40, which feed pump in turn has its intake connected with a reservoir 41. The pump 40 is 50 driven by the shaft 42 connected directly to a power take-off of a motor 43. Said pump 40 should be of a type which has an adjustment for regulating the volume delivery under constant load conditions. The motor 43 is belted to the 55 pulley 19 and pulley 37 in such a ratio of gearing that the pulley 19 is rotated at a speed less than that of the prime mover and the pulley 37 rotates at a speed in excess of that of the prime mover. These ratios are further proportioned so that 60 pulley 19 is operated at a rotational speed to deliver the proper amount of dust material to the dispersing tube 28.

A valve 44 is disposed in either the discharge or the supply line of the pump 40 (the drawing shows the valve in the delivery side), and it is 65 actuated concurrently with the slide valve 27 by means of links 47, 48 and 49, and a lever 45. This arrangement provides simultaneous control for the release of the impounded dust and adhesive.

70 The operation of this invention is as follows: Material in dust form is placed in hopper 5. Material in liquid form to be used as an adhesive, such as fish oil, paraffin oil, and mineral oil, is 75 placed in reservoir 41. To prevent discharge of

these substances from their respective containers, slide valve 27 and control valve 44 remain in a closed position. To operate the apparatus, the motor 43 is started. This function results in the rotation of conveyor screws 9 and 12 in opposite directions. At the same time the positive feed pump 40, which is directly connected to the power unit, is put in motion. Coincident with the started motion of the conveyor screws and the pump, the tube 30 is rotatably actuated, together with cone 33 and disc 34. With the apparatus as shown in the drawing, it is necessary that the vehicle upon which the apparatus is mounted be set in motion at a speed sufficient to cause a circulation of air through the members 29, 29 into the dispersing tube 28 and with a sufficient force to entrain the dust which is to be discharged into the tube 28. It has been found that speeds of forty miles per hour or higher are satisfactory for the particular apparatus shown and to obtain the particular results desired. When the lever 45 is placed in the position resulting in the simultaneous opening of the slide valve 27 and the control valve 44, the dust material discharged from the hopper onto the conveyor screw 9 is advanced toward one end of the conveyor screw 9 and hence dropped onto the respective end of the conveyor screw 12. Consequently, it is advanced toward the discharge opening immediately above the slide valve 37, thence through valve 27 into the dispersing tube 28. As soon as the dust falls into said dispersing tube, the air stream, introduced into the tube by means of the air scoops 29, 29, imparts a spiral revolution to the dust and advances it 34 toward the opening in the other end of the tube between the flange 36 and the lateral exterior surface of the cone 33. The shape of the bell flange 36 determines the angle with which the dust leaves the tube 28 at any given speed. At the same time the pump 40 delivers the adhesive 40 material in the reservoir 41 through the stationary tube 38 releasing it at its terminal within the cone 33. The force of the delivery of this material is such that it impinges upon the plate 34 and due to the rotation of said plate 34, the 45 centrifugal force moves the particles of this liquid material toward the periphery of said plate 34, and in leaving the plate 34 impinges upon the inside lateral surface of the cone 33. 50 The plate 34 should be adjusted to such a position that when the adhesive material leaves it, it will impinge upon the cone 33 as close as possible to its outer edge. With this arrangement, the dust and the adhesive emitted will both be 55 in the form of a whirling cone. However, the cone of the dust material will have a smaller apex angle than the cone of the adhesive material, and consequently, the adhesive material will intersect the cone of the dust material in a 60 plane at a considerable distance away from the apparatus, such distance depending upon the velocity of the air stream flowing through and around the dispersing tube 28. 65 The adhesive material striking plate 34 is thrown out by centrifugal force to its periphery. Due to the high peripheral speed of disc 34, the adhesive at that point is broken up into droplets. Leaving the periphery, these droplets strike the 70 inside of the cone 33, the peripheral velocity of which is greater than the peripheral velocity of plate 34, and accordingly these droplets undergo an acceleration which causes a further breaking up into still smaller droplets. Also, when these 75

adhesive, said conical stream of adhesive having a larger apex angle than said conical air stream.

13. A device for dispersing and coating dust particles with an adhesive therefor, said device comprising means for uniformly entraining particles of dust in an external turbulent conical air stream and means for intersecting said conical air stream with a turbulent conical transverse stream of adhesive, said conical stream of adhesive having a larger apex angle than said conical air stream.

14. A device for dispersing and coating dust particles with an adhesive therefor, said device comprising means for uniformly entraining particles of dust in an external conical air stream, a hollow truncated cone rotatably mounted in the path of said air stream, a disc fixedly mounted on the exterior of said cone substantially coincident with and smaller than the larger base of said cone, and means for impinging a stream of liquid against the inner face of said disc when rotating.

15. A device for dispersing and coating dust particles with an adhesive therefor, said device comprising means for uniformly entraining particles of dust in an external conical air stream, a hollow truncated cone rotatably mounted in the path of said air stream, a disc fixedly mounted on the exterior of said cone substantially coincident with and smaller than the larger base of said cone, and means for controllably impinging a stream of liquid adhesive against the inner face of said disc when rotating.

16. A device adapted to be mounted in an air vehicle for dispersing dust particles and an adhesive therefor, said device comprising a dust hopper, a continuous flight conveyor screw horizontally mounted in the delivery throat of said hopper, another flight conveyor screw mounted parallel and directly below, said first mentioned conveyor screw being rotatably mounted in communicating tubular troughs, gears keyed to extended shafts of said conveyor screws, said gears being maintained in constant mesh, means for discharging matter from the lower conveyor screw to a longitudinal dispersing tube, air vents tangentially disposed on said dispersing tube in the general direction of travel of the air vehicle, a hollow tube rotatably mounted axially within said dispersing tube, a truncated cone having its truncated end secured to the end of said hollow tube on the interior of said dispersing tube, a disc adjustably mounted on the exterior of said cone, substantially coincident with and smaller than the larger base thereof, a stationary tube fixedly mounted within said rotatably mounted hollow tube and extending within said cone between its apex and said disc, means for forcing a liquid adhesive through said stationary tube, and means for directing a continuous volume of air through said air vents.

17. The method of dispersing parasitical dust

particles with an adhesive, said method consisting of substantially rotating and coating particles of dust with particles of the adhesive.

18. A device for dispersing and coating dust particles with an adhesive comprising a dispersing tube, means for producing an air stream through said tube, means for introducing dust material into said dispersing tube, means for regulating the quantity of dust material introduced in said dispersing tube, means for uniformly entraining the dust material in said air stream, means for discharging the stream conically, a source of liquid adhesive for said dust material, and means for discharging said adhesive transversely to said stream.

19. A device for dispersing and coating dust particles with an adhesive, comprising a dispersing tube, means for producing an air stream through said tube, means for introducing dust material into said dispersing tube, means for regulating the quantity of dust material introduced in said dispersing tube, means for uniformly entraining the dust material in said air stream, means for discharging the stream conically, a source of liquid adhesive for said dust material, means for discharging said adhesive in a cone transverse to said stream, and means for quantitatively regulating the discharge of adhesive.

20. A device for dispersing and coating dust particles with an adhesive, comprising a dispersing tube, means for producing an air stream through said tube, a source of dust material, a valved opening in said dispersing tube, means, including flight conveyor screws, for feeding and regulating the delivery of dust material from said source to said valved opening, means for uniformly entraining the dust delivered to said dispersing tube in the air stream therethrough, means for discharging said stream conically, a source of adhesive, and means for discharging said adhesive in a cone transverse to said air stream.

21. A device for dispersing and coating dust particles with an adhesive, comprising a dispersing tube, means for producing an air stream through said tube, means for introducing dust material into said dispersing tube, means for regulating the quantity of dust material introduced in said dispersing tube, means for uniformly entraining the dust material in said air stream, means for discharging the said stream conically, a source of liquid adhesive for said dust material, a hollow tube rotatably mounted longitudinally within said dispersing tube, a truncated cone having its narrow end secured to the end of said hollow tube, a disc secured to said cone perpendicular to its axis, means for controllably forcing material from said source of liquid through said hollow tube, and means for rotating said disc.

A. GORDON GALLOWAY.

droplets of the adhesive leave the cone 38, they are further reduced in size by atomization.

At the point of intersection of the cone of the adhesive and the cone of the dust particles, both materials are in the form of finely divided particles, the dust being entrained in a cloud of uniform density, and the adhesive material being in an atomized form. Also the particles are very small, no larger than what is necessary for one particle of adhesive to coat itself about one particle of dust. Ideally, the number of dust particles and the number of adhesive particles dispersed over a period of time should be equal. The theory of this coating process is that each particle of adhesive upon contact with a dust particle intercepts and draws this dust particle within it due to its great surface tension. The maximum percentage of mixture takes place at the point of intersection of the two cones. However, the efficiency of union is not 100 per cent at this point, and some of the particles are bound to escape a union here. However, due to the turbulent effect of both cones, union may take place at points further removed from the apparatus than this plane of intersection, and, as a matter of fact, could even take place upon contact with the surface to which the material is being applied. It is desirable to use an adhesive of such density that the atomized particles upon dispersion are of the same weight as the dust particles and no larger than what is necessary for one particle of adhesive to coat itself about one particle of dust. The size of the adhesive particles may be regulated by controlling the flow of adhesive by adjustment 46 on the pump 48, by changing the rotational speed of the cone 38 and disc 34, or both.

The purposes of the two conveyor screws are, first, to provide for positive control of feeding the dust material from opening 5 through slide valve 27 to dispersing tube 28, and second, to furnish an arrangement whereby the dust material can be satisfactorily prevented from packing when slide valve 27 is closed. In accomplishing this, the dust material, when conveyed by screw 12 past the opening leading to slide valve 27, is moved to the end of said screw 12, hence up to screw 9, which delivers the dust again to screw 12, thus providing a circulating path for the dust material. A third purpose of these conveyor screws is to provide for vibration to prevent packing of the dust in the bottom of hopper 5.

Should it be desired to use this apparatus in a stationary position as differentiated from use on a vehicle moving through the air scoops 29, 29 may be substituted with other suitable means for forcing air into the dispersion tube 28. Such means may consist of a compressed air pump, blower fan, or other means.

While this invention has been described as taking a particular form for the purpose of illustration, it is not to be assumed that other forms may not be used by changing the form and shape of the materials used within the scope of the appended claims.

Having thus described my invention, I claim:

1. The method of dispersing and coating particles of dust with an adhesive, said method consisting of entraining individual particles of said dust in an external air stream and intersecting said dust particles with particles in another air stream, said last mentioned particles consisting of the adhesive in finely divided form.
2. The method of dispersing and coating dust with an adhesive, said method consisting of entraining particles of said dust in an external conical air stream and intersecting the dust particles in said air stream with particles of the adhesive entrained in a finely divided form in a transverse conical stream, said conical stream of adhesive having a larger apex angle than said conical air stream.
3. The method of dispersing and coating dust with an adhesive, said method consisting of entraining particles of said dust in an external conical air stream and intersecting the dust particles in said air stream with particles of the adhesive entrained in a finely divided form in a transverse conical stream, said conical stream of adhesive having a larger apex angle than said conical air stream.
4. The method of dispersing and coating dust with an adhesive therefor, said method consisting of entraining particles of dust in an external conical air stream and intersecting said air stream with a transverse conical stream of the adhesive in a finely divided form, said conical stream of adhesive having a larger apex angle than said conical air stream.
5. The method of dispersing and coating dust with an adhesive therefor, said method consisting of entraining particles of said dust in an external turbulent conical air stream and intersecting the dust particles in said air stream with a transverse conical stream of the adhesive in a finely divided form, said conical stream of adhesive having a larger apex angle than said conical air stream.
6. The method of dispersing and coating dust with an adhesive therefor, said method consisting of intercepting air-entrained particles of the dust with air-entrained particles of the adhesive.
7. The method of dispersing and coating dust with an adhesive therefor, said method consisting of intercepting entrained particles of said dust in an external rotating conical air stream with particles of the adhesive entrained in a transverse rotating conical air stream.
8. A device for dispersing and coating dust particles with an adhesive therefor, said device comprising a dispersing tube horizontally mounted, means for creating a flow-stream of air in said dispersing tube, means for controllably introducing the dust into said flow-stream and discharging it conically from said dispersing tube, and means for intersecting the particles in said flow-stream with a transverse conical stream of finely divided adhesive.
9. A device for dispersing and coating dust particles with an adhesive therefor, said device comprising means for entraining particles of dust in an external conical air stream, and means for intersecting the particles in said conical air stream with a transverse conical stream of the adhesive.
10. A device for dispersing and coating dust particles with an adhesive therefor, said device comprising means for uniformly entraining particles of dust in an external conical air stream, and means for intersecting said conical air stream with a transverse conical stream of adhesive.
11. A device for dispersing and coating dust particles with an adhesive therefor, said device comprising means for uniformly entraining particles of dust in an external conical air stream and means for intersecting said conical air stream with a transverse conical stream of adhesive, said conical stream of adhesive having a larger apex angle than said conical air stream.
12. A device for dispersing and coating dust particles with an adhesive therefor, said device comprising means for uniformly entraining particles of dust in an external turbulent conical air stream and means for intersecting said conical air stream with a transverse conical stream of adhesive.
